US0D1076539S

(12) **United States Design Patent** (10) **Patent No.:** **US D1,076,539 S**
(45) **Date of Patent:** **** May 27, 2025**

(54) **DECANTER**

(71) Applicant: **Shenzhen Tiangao Renniaofei Technology Group Co., Ltd.**, Shenzhen (CN)

(72) Inventor: **Canqiang Zhang**, Chaozhou (CN)

(73) Assignee: **Shenzhen Tiangao Renniaofei Technology Group Co., Ltd.**, Shenzhen (CN)

(**) Term: **15 Years**

(21) Appl. No.: **29/960,796**

(22) Filed: **Sep. 2, 2024**

(51) **LOC (15) Cl.** **09-01**

(52) **U.S. Cl.** **D7/301**
USPC **D7/301**

(58) **Field of Classification Search**

(57) **CLAIM**

The ornamental design for a decanter, as shown and described.

DESCRIPTION

FIG. 1 is a top, front, right side perspective view of a decanter showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the decanter shown in its use state.
The broken lines depict the environmental subject matters of the decanter that form no part of the claimed design.

1 Claim, 9 Drawing Sheets
